ATT'Y.

UNITED STATES PATENT OFFICE.

WILLIAM H. WILKINSON, OF BOSTON, MASSACHUSETTS.

MEANS FOR SUPPORTING ELECTRIC LAMPS AND ENERGIZING AND LIGHTING SAME.

SPECIFICATION forming part of Letters Patent No. 778,618, dated December 27, 1904.

Application filed April 29, 1904. Serial No. 205,621.

To all whom it may concern:

Be it known that I, WILLIAM H. WILKINSON, a citizen of the United States, residing at Boston, county of Suffolk, and State of Massachusetts, have invented certain new and useful Improvements in Means for Supporting Electric Lamps and Energizing and Lighting the Same, of which the following is a specification, reference being had to the drawings accompanying the same.

My invention relates to means for supporting an electric lamp and for energizing and lighting the same at the convenience of the operator.

The object of my invention is to produce a convenient means for lighting the faces of gages, clocks, or similar devices attached to or used in connection with carriages or automobiles or when placed in a location where it is desirable to occasionally illuminate their faces.

In the drawings illustrating my invention, Figure 1 is a diagrammatic view illustrating my improved electric-lamp support with a lamp attached, secured contiguous to a pair of pressure-gages with push-button and storage battery and line-wiring connecting the storage battery with the lamp. Fig. 2 is a diagrammatic side elevation showing the gages, storage battery, lamp, and lamp-support through line 2 2, Fig. 1. Fig. 3 is a sectional elevation of a lamp and lamp-bracket through line 3 3, Fig. 2. Fig. 4 is a plan view of the bottom of my improved push-button used in connection with a lighting device, and Fig. 5 is a partial sectional elevation of the push-button shown in Fig. 4.

In the drawings, A represents a storage battery of any suitable element, cylindrical in shape, having contacts A' and A² at the ends thereof, said battery A being held in the spring-clamps B B, attached to a board C by any suitable means.

C' and C² are contact-springs adapted to contact with the contact-points A' and A² of the storage battery at one of their ends, the other ends of said springs being secured to the board C by suitable screws.

D is a lamp-bracket having a socket D' attached thereto. D² represents a filament. The

lamp-bracket D is provided with the cowl or reflector D³, which cowl D³ is used to shade the light from the eyes of the operator as well as to cause it to be reflected forward and upon the faces of the gages to be lighted.

E is the body of a push-button which may be made of any suitable material and is provided with an opening E', adapted to receive the plug E². Said plug E² contains the spring-return push-button E³, which is provided with a metal pin E⁴, attached to its lower end. The plug E² is provided with rubber insulation, to which is attached contact-springs F and F' by means of suitable screws F² and F³. The pin E⁴ is so adjusted that by pressing on the top of the button E³ it is pushed down to contact with the inwardly-projecting ends of the contact-springs F and F'. The body part E is provided with a slot E⁵, through which the wires can pass which are connected to the contact-springs F and F'. The electrical energy of the storage battery may be intermittently supplied to the lamp D² through the push-button pin E⁴ by means of its contact with the springs F and F', bridging or completing the circuit.

G is a line-wire leading from the contact-spring C' to the screw F² on the contact F.

G' is a wire leading from the screw F³ of the contact-spring F' to the screw-terminal D⁴ of the lamp-socket.

G² is a wire leading from the binding-screw D⁵ of the lamp-socket to the contact-spring C² of the storage battery, thus completing the circuit from the contact A' of the storage battery through the push-button E, the lamp D² by wire G to the contact A² on the opposite end of the storage battery A, this circuit being completed by pressing the button E³ and bringing the contact-pin E⁴ in contact with the terminals of the contact-springs F and F'. When the pressure is removed from the push-button E³, it is returned by any suitable spring means to a normal position, thereby moving the contact-pin E⁴ away from the contact-springs F and F', thus breaking the circuit.

The wires G, G', and G² may be of any suitable length and flexible, so that the storage battery A and the push-button E may be lo-

cated at any point convenient to the operator. Hence the location of the elements in my lighting device as set out in Fig. 1 are not essential to the operation of the device, as 5 they may be arranged in any suitable manner with relation to each other and at any suitable distance apart.

The object of the springs B B and the flexible contact-springs C' and C² is that the storage battery A may be readily removed when 10 the electric energy therein has been discharged and a new one inserted without breaking the contact of the wires or disconnecting them. Likewise the plug E² may be readily removed 15 from the body part E by loosening the set-screw H. The wires G and G' will slide out through the slot E⁵ without disconnecting them from the contact-screws F² and F³ or without removing the body part E from the 20 object to which it is attached.

Having described my invention, what I claim is—

1. In a device for illuminating the pressure-gages of an automobile, the combination of an 25 electric lamp; a lamp-support provided with means for attaching it to the support of the gages; a socket to removably receive said lamp; a shield to reflect a light upon the gages and shield it from the eyes of the operator; a storage battery; a support for said storage battery 30 provided with flexible contact-springs; spring-clamps for removably holding the storage battery in position with its terminals in contact

with said contact-springs; flexible wires connecting said contact-springs with the terminals of the lamp-filament; and means interposed in one of said wires for making and breaking the electrical contact. 35

2. An electrical illuminating device for pressure-gages and the like, comprising an 40 electric lamp; a lamp-bracket; a socket in one end of said lamp-bracket adapted to removably support the lamp; a shield attached to one end of said lamp-bracket; means on the other end of said bracket for attaching it to the gage-support; a storage battery; a support for said storage battery; flexible contact-springs on 45 said support; flexible clamping means on said support in which the storage battery may be removably held in position to permit said contact-springs to contact with its terminals; flexible wire connections connecting the terminals of the storage battery with the terminals of the lamp-filament; a push-button inserted in one of said flexible wire connections, 50 arranged to be located convenient to the hand or foot of the operator.

In testimony whereof I have hereunto set my hand, in the presence of two subscribing witnesses, this the 25th day of April, A. D. 60 1904.

WILLIAM H. WILKINSON.
